(57) **CLAIM**

The ornamental design for an electronic console, as shown and described.

DESCRIPTION

FIG. 1 is an isometric view of an electronic console showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view taken through line 8-8 of FIG. 6, showing the concave upper region of the electronic console.

The even-length broken lines in FIGS. 1-8 illustrate portions of the electronic console that form no part of the claimed design. The uneven-length broken lines in FIG. 8 illustrating the enlarged detail view, are for annotative purposes and form no part thereof.
